WRAPPING MACHINE

Wilhelm B. Bronander, Montclair, N. J.

Application February 12, 1942, Serial No. 430,566

8 Claims. (Cl. 93—2)

This invention relates to wrapping machines.

The invention has for its object to provide a simple and practical wrapping machine so constructed and arranged as to operate at high speed and efficiently and to form a neat, tight package.

Further objects of the invention will appear from the following specification taken in connection with the drawings which form a part of this application, and in which

Fig. 1 is an elevational view of a machine constructed in accordance with the invention;

Fig. 2 is an enlarged sectional elevation taken substantially on line 2—2 of Fig. 3;

Fig. 3 is a top plan view of the machine shown in Fig. 1 taken on line 3—3 of Fig. 2;

Fig. 4 is a sectional elevation taken substantially on line 4—4 of Fig. 2;

Fig. 5 is a sectional elevation taken substantially on line 5—5 of Fig. 2;

Fig. 6 is a detail elevational view showing the Geneva drive for the turret wheel;

Fig. 7 is a plan view of the blank in which the package is wrapped;

Fig. 8 is a perspective elevation of the package after the blank has been folded around the package and secured along one longitudinal edge thereof, before the ends of the package have been closed; and

Fig. 9 is a perspective view of the completed package.

The invention briefly described consists of a wrapping machine having means for feeding a wrapper strip in the path of movement of the articles to be wrapped, means for holding the strip tightly around the top, bottom and one end of the package as it is cut, a turret wheel having radially disposed pockets for receiving the wrappers and articles, means engageable with the rearwardly projecting ends of the wrapper to fold these ends across one side of the article, means for discharging the articles and wrappers folded therearound into folding mechanism by means of which the ends of the wrapper are closed and sealed. In connection with this mechanism, means is provided for applying adhesive to the bottom rearwardly extending flap as the article and wrapper are discharged from the first feeding means and are fed into the pocket in the turret wheel. Certain novel features are also incorporated in the end flap folding mechanism and in other parts of the mechanism, as will be herein-after described.

Further details of the invention will appear from the following description.

In the form of the invention particularly illustrated, the machine comprises longitudinal frame members 10 and vertical frame members 11. A hopper 12 is supported above the longitudinal frame members and houses the articles A to be wrapped.

The articles drop by gravity through an opening 13 in a stationary top plate 14 to a bottom plate or table 15 which is pivotally mounted at 16. The table 15 is engaged by springs 17 and 18 which force it upwardly, thus holding the wrapper tightly against the under surface of the article being wrapped. The upward movement of the table 15 is limited by a bolt 19 having a lock nut 20 thereon.

10 The articles A which, as above stated, drop by gravity to the table 15, are engaged and fed by feeding members or rods 25 carried by feed chains 26 and 27. The table 15 is provided with an opening 28 through which the wrapper strip W is fed in a manner which will now be described.

The feeding mechanism for feeding a tear strip T and the wrapper strip W in superposed relation is not shown in detail since this mechanism forms no part of the present invention. As illustrated diagrammatically in Fig. 1, the tear strip T is carried by a roll 30 and is fed between feed rolls 31 and 32 and around an idler 33 and thence between feed rolls 34 and 35.

20 The wrapper strip W is carried by a roll 36 and is led beneath an idler 37 and around the roll 35, passing between the rolls 34 and 35.

As the strip W passes around the idler 37 it is engaged by an H-shaped knife 38 carried by a roll 39 and an H cut is formed therein.

30 As the strips W and T pass between the rolls 34 and 35 the tear strip T is pushed into a pocket 40 formed in the roll 35 by a projecting lug 41 carried by the roll 34. After passing between the rolls 34 and 35 the tear strip T is cut by a 35 knife 43 carried by a roll 44. The wrapper strip with the superposed tear strip are then fed downwardly between rolls 45 and 46 and the wrapper and tear strip are cut by a knife 47 carried by a roll 48, the knife 47 coacting with a stationary 40 knife 49.

The operation of the knives 47 and 49 is so timed that the strip will not be cut until it has been engaged by the article fed along the support or plate 15 and has been folded beneath the article. The upward pressure of the table 15 will hold the wrapper strip tightly against the upper and lower surfaces of the article as the article is fed between the plate 14 and table 15 and as the wrapper is cut.

50 The upper plate 14 is interrupted, as shown in Fig. 2, to permit the wrapper strip to pass downwardly through an opening 50 formed therein and through the opening 28 in the lower table 15. As the article and wrapper are fed forwardly the 55 wrapper is folded across the bottom, advance end and top of the article and the article and wrapper are discharged into one of a plurality of radially disposed pockets P carried by an intermittently rotatable turret wheel 55 mounted on a shaft 56.

60 Each pocket P has a stationary wall 57 and a

pivoted wall 58. The pivoted wall is pressed toward the stationary wall by a spring 59 which is disposed between the wall 58 and a bracket 60.

As shown in Fig. 3, the shaft 56 has two turret wheels 55 mounted thereon, these wheels being spaced apart and being provided with aligned, exactly similar pockets P. The walls of these pockets receive the end portions of the article and wrapper as the article and wrapper are discharged from the supporting table 15.

As the article and wrapper are fed into the pockets liquid or adhesive is applied to the under surface of the rearwardly projecting lower flap 61. The upper flap is designated 62. The adhesive is applied in the following manner: As the feeding member or rod 25 pushes the article and wrapper into the pockets the rod passes downwardly and during its downward movement engages the flap 61 and presses the flap against a moistening wick 63 carried by a bracket 64 mounted on a shaft 65. The bracket 64 has a well 66 for the moistening or adhesive material. It will be noted that the under surface of the lower flap 61, as shown in dotted lines in Fig. 2, is pressed against the wick 63 and is receiving adhesive or solvent therefrom.

From the showing in Figs. 2 and 3 it will be seen that the shaft 65 has mounted on one end thereof an arm 67, the outer end of which is normally held downwardly by a spring 68. In its downward position the arm 67 rests on an arm 69 carried by a spindle 70. If the arm 69 is rotated in a clockwise direction, the arm 67 will be similarly rotated, thus tilting the bracket 64 and moistening wick 63 downwardly out of operative position. This is done manually and when the machine is not in use.

The turret wheels 55 and shaft 56 are rotated intermittently by a Geneva movement which is illustrated particularly in Fig. 6, but the details of which form no part of the present invention.

The main drive shaft of the machine is shown in Fig. 1 at 75. This shaft is rotated from any suitable source of power and has mounted thereon a gear 76 which meshes with a gear 77 carried by a shaft 78. The shaft 78, as shown in Fig. 6, carries a disk 79 on which are mounted a pair of rollers 80 and 81. These rollers are arranged to engage pear shaped lugs 82 radially mounted on a disk 83 carried by the shaft 56. By means of this Geneva movement the shaft 56 will be rotated intermittently in increments of movement, the rotation of movement in each instance being sufficient to rotate the shaft through one-sixth of a revolution or 60°, it being understood that this angle of movement is determined by the number and spacing of the radially arranged pockets P.

After the shaft has been rotated through two increments of movement or through 120°, the outwardly projecting ends 61 and 62 of the wrapper are folded against the outer surface of the article in the manner which will now be described. The flap 61 is first engaged by an arcuate folding plate 85 carried by an arm 86 rotatably mounted on a shaft 88 (Figs. 2 and 4). The arm 86 has secured thereto a sleeve 89 which carries at its outer end an arm 90. The arm 90 is pivoted at 91 to a link 92 which is pivoted at its opposite end to an eccentric strap 93 mounted on an eccentric 94 carried by a shaft 95. As the eccentric rotates the link 92 will be oscillated, thus moving the folding plate 85 alternately in opposite directions. Since the surface engaged by the plate 85 has liquid or adhesive thereon

the plate is grooved, as shown at 96, to provide spaced portions for engaging the flap.

The flap 62 is folded downwardly on the flap 61 by an arcuate plate 98 carried by an arm 99 fixed to the shaft 88.

The shaft 88 has secured to its outer end an arm 100 to which is pivoted a link 101, the other end of which is pivoted to an eccentric strap 102 mounted on an eccentric 103 carried by the shaft 95. The eccentric is so designed that the plate 98 will be moved in a clockwise direction viewing Fig. 2 after the flap 61 has been folded and plate 98 will engage and fold the flap 62 downwardly over the flap 61 before the flap 61 has been entirely released or disengaged by the plate 85.

In order to facilitate and expedite the sealing of the end flaps the plate 98 is mounted above a heater 105 carried by arms 106 and 107 mounted on the shaft 88. The arms 106 and 107 are held in stationary position by a rod 109 which extends through the lower ends thereof and is fixed to the upright frame of the machine. Suitable insulation 110 is preferably provided between the arms 106 and 107 and above the folding plate 98.

The shaft 95 has mounted thereon a gear 112 which meshes with the gear 77 on the shaft 78.

Shaft 78 has also mounted thereon a gear 113 which meshes with a gear 114 carried by a shaft 115. This shaft has secured thereto sprocket wheels 116 on which are mounted chains 117 which carry feeding members or lugs 118. The chains 117 are also mounted on idler sprocket wheels 120.

The lugs 118 pass upwardly between the aligned pockets P on the turret wheel 55 and engage and feed the articles and wrappers which have been folded therearound from the pockets to a support or table 121.

The shaft 115 has also mounted thereon outside the chains 117 a pair of disks 125 and 126 (Fig. 4). Each disk has projecting from the periphery thereof a plurality of blades 127 which are adapted to engage and tuck the wrapper at the rear edge of the package, it being understood that the ends of the wrapper extend beyond the ends of the package at this point in the operation of the machine, as shown in Fig. 8.

The front ends of the wrapper are tucked by stationary tuckers 130 disposed at the sides of the support 121.

It will be understood that after the ends of the wrapper have been tucked a flap will be projected at each end in alignment with the upper and lower surfaces of the wrapper. These flaps are folded inwardly to close the wrapper by means of slots 131 and 132 in walls disposed at the sides of the support 121.

The feed chains 26 and 27 are carried by sprocket wheels 135, 136 mounted on a shaft 137. This shaft has also secured thereto a gear 138 which meshes with the gear 77 on shaft 78. The chains 26 and 27 are also led around sprockets 139, 140 and 141.

The feeding and cutting mechanism for the wrapper strip and tear strip are driven by suitable gear driving connections from the shaft 145 which carries the roll 48 and knife 47. Shaft 145 has mounted thereon a gear 146 which meshes with a gear 112 mounted on the shaft 95.

The operation of the machine can be briefly summarized as follows: The articles A drop by gravity on the pivoted supporting table 15 and are fed along this table and beneath the plate

14 by feeding members 25. The springs 17 hold the plate 15 upwardly into engagement with the wrapper and press the wrapper firmly between the upper and lower surfaces of the article and the plate 14 and table 15, respectively.

As the article and wrapper are discharged from the table 15 and are fed into the pockets P the bottom flap 61 is engaged and bent downwardly against the wick 63 which applies liquid or adhesive thereto.

The turret wheel 55 which carries the pockets P is rotated intermittently by the Geneva movement described and when the article and wrapper have been moved through two increments or 120° the folding plate 85 is moved from the dotted line position shown at 85A in Fig. 2 to the full line position shown at 85, thus engaging the flap 61 and folding the flap downwardly against the side of the article. Thereafter the folding plate 98 is moved in a clockwise direction, thus folding the other flap 62 downwardly against the flap 61. The folding plate 98 is heated by the heater 105 and thus assists in expediting the sealing of the flaps 61 and 62.

The turret wheel then moves through another increment of movement or 60° and the tuckers 127 and the stationary tuckers 130 operate to tuck the projecting ends of the wrapper. The heater has an arcuate surface 105A which engages the folded flaps 61, 62 during this movement. The article and wrapper are then moved along the support 121 by the feeding lugs 118 and during this movement the end flaps are folded to closed position by the slots 131 and 132. Heat sealers may be provided beyond the folding slots to facilitate and complete the sealing operation.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In a wrapping machine, a movably mounted supporting table for receiving articles to be fed and wrapped, a stationary top plate above and spaced from said table, means for resiliently moving the table toward the plate, said plate and table having aligned openings to receive a wrapper strip, means for feeding articles along said table, and means for feeding a wrapper strip through the openings and in the path of movement of the articles fed along the table.

2. In a wrapping machine, a movably mounted supporting table for receiving articles to be fed and wrapped, a stationary top plate above and spaced from said table, means for resiliently moving the table toward the plate, said plate and table having aligned openings to receive a wrapper strip, means for feeding articles along said table, means for feeding a wrapper strip through the openings and in the path of movement of the articles fed along the table, and means operable to sever the wrapper strip after said strip has been engaged and positioned on an article fed along the table and while the wrapper strip is engaged between the article and the stationary plate.

3. In a wrapping machine, a pivotally mounted supporting table for receiving articles to be fed and wrapped, a stationary top plate above and spaced from said table, means for resiliently moving the table toward the plate, said plate and

table having aligned openings to receive a wrapper strip, means for feeding articles along said table, and means for feeding a wrapper strip through the openings and in the path of movement of the articles fed along the table.

4. In a wrapping machine, means for feeding articles to be wrapped, means for disposing wrappers across the advanced end, the top and bottom of said articles, a plurality of movable pockets, said article feeding means being arranged to

push the articles into said pockets with both ends of the wrappers projecting rearwardly from the pockets beyond the rear ends of the articles therein, and a stationary liquid applying device 15 stationed below the lower rearwardly projecting ends of the wrappers, said article feeding means being arranged to depress said lower projecting ends of the wrappers across the liquid applying device.

20 5. In a wrapping machine, means for feeding articles to be wrapped, said feeding means comprising endless driving means and feeding members carried thereby, means for disposing wrappers across the advanced end, the top and bottom

25 of said articles, a plurality of movable pockets, said article feeding means being arranged to push the articles into said pockets with both ends of the wrappers projecting rearwardly from the pockets beyond the rear ends of the articles there-
30 in, and a stationary liquid applying device sta- tioned below the lower rearwardly projecting ends of the wrappers, said article feeding members be- ing arranged to depress said lower projecting ends of the wrappers across the liquid applying device.

35 6. In a wrapping machine, means for feeding articles to be wrapped a stationary top plate arranged to engage the upper sides of the articles, said plate being constructed with a transverse slot, means for continuously feeding a wrapper strip through said slot across the path of movement of the articles, and resiliently actuated means for forcing the articles upwardly against said guide and positioning and pressing the wrappers against the upper and under surfaces of the

40

45 articles as the articles are being fed.

10 7. In a wrapping machine, a pocket, means for
feeding articles to be wrapped into said pocket,
means for disposing wrappers across the top, ad-
vance end and bottom of said articles with the
50 ends of the wrappers extending rearwardly from
the pocket beyond the rear ends of the articles,
a liquid applying device positioned below the low-
er rearwardly projecting ends of the wrappers,
said article feeding means being arranged to
55 move said lower end of the wrapper onto the liq-
uid applying device, and means for moving the
liquid applying device out of operative position.

8. In a wrapping machine, a pocket, means for feeding articles to be wrapped into said pocket, said feeding means comprising a pair of axially aligned spaced sprockets positioned near the pocket, endless chains having straight runs passing around said sprockets and a transverse member affixed to the chains, means for disposing a wrapper strip across the path of movement of the articles whereby an article and a wrapper strip are fed into the pocket by the transverse member while on a straight run of the chains with the ends of the wrapper extending from the pocket, a liquid applying device parallel with and at one side of the pocket, said feeding member being arranged to move one of the extending ends of the wrapper onto the liquid applying device as the chains run around the sprockets.

WILHELM B. BRONANDER.
